MACHINE FOR FIXING LOCKS, FASTENINGS,
AND FITTINGS TO ATTACHE AND SIMI-
LAR CASESCharles William Cheney, Soho, Birmingham,
EnglandApplication September 9, 1936, Serial No. 100,005
In Great Britain September 12, 1935

4 Claims. (Cl. 1-4)

This invention has reference to a machine for fixing pronged locks, fastenings and fittings, hereinafter referred to as fastenings, to pre-shaped case bodies or lids of attaché and similar travelling cases made of cardboard, leather, fibre and the like, hereinafter referred to as "material".

The invention particularly relates to a machine of the press class of the kind comprising a bed supporting a number of adjustable bottom tools and a plunger carrying a number of adjustable combination top tools, the operation of the machine being such that when the fastenings are placed prong-upwards in the bottom tools the top tools descend with the plunger to force the material, to which the fastenings are to be attached, downwardly for penetration by the prongs and hold said material under penetrating pressure while parts of the top tools operate to clinch the prongs, one or more fastenings being attached to the material for each descent of the plunger.

The above features are embodied in a machine forming the subject of U. S. Letters Patent No. 1,955,790 granted to me on April 24, 1934.

While the said patented machine marks a definite advance in the fixing of fastenings, it must be understood that in this machine the fastenings could be fixed to the material only when the latter was still in the form of a flat blank, that is to say, before it was shaped into a case body or lid, because the particular construction of the said machine precluded a case body or lid on account of the side walls from being placed in position and operated on by said tools. As a result the flat blanks having fastenings fixed to them had to be subsequently shaped-up into case bodies and lids and then to be sewn and finished, which is well-known to those skilled in the art to be a rather inconvenient operation.

The object of the present invention is to provide a machine which admits of said fastenings being secured to case bodies or lids, which have been brought before into the desired shape.

The invention consists of an improved machine having the combination of parts hereinafter described with reference to the accompanying drawing.

Fig. 1 is a sectional elevation of the machine with the top tools lifted by the plunger action. Fig. 2 is a sectional side elevation of Fig. 1 but with the top tools removed for clearness of illustration and indicating in broken lines an attaché case body having its final shape in a position ready for the fixing of fastenings thereto.

Fig. 3 is a plan.

Fig. 4 is an elevation of a lock fastening to be fixed by the tools illustrated, and

Fig. 5 is a sectional side view of a top tool.

The machine illustrated has the general characteristics of a press; a table 1 is supported by a frame 2 and is provided with a rigid rear pillar 3 having a vertical slide-way 4 on which a plunger head 5 is adapted to reciprocate. The plunger-head 5 rigidly supports a horizontally extending bar-like carrier 6 upon which a pair of tool holders 7 are mounted to be longitudinally slidable from end to end and adjustable to any intermediate or central position, said tool holders 7 being adapted to be retained in adjusted positions by means of lever catches 8, carried by the holders, co-operating with spaced notches 9 formed in the upper edge of the carrier 6, and to be fixed in said positions by screw-actuated clamping devices 10, 12. A tool holder 7 is first positioned through the lever catch 8 and afterwards the screw 10 is tightened to fix the holder to the carrier 6.

Said tool holders 7 are provided at their lower ends with forwardly disposed or offset projections 13, said projections being vertically gapped at 14. The forward ends of the projections 13 are adapted to receive, in a readily detachable manner combination tools, 15, comprising an angular sleeve 16 to fit over the gapped end 14, a pressure plate 17 vertically displaceable against a compressible spring 18, said pressure plate carrying pivoted clinching flaps 19, and clinching pegs 20 rigidly fixed to the base of said sleeve. Each of said tools is adapted to be removably fixed to the offset projection 13 by means of a lever catch 21, the spring 18 being received in the gap 14. The tools 15 are compactly constructed, that is to say, they are symmetrical and devoid of any abnormal projecting parts in their length, breadth and depth, and therefore do not preclude or hinder the tools actually working within a case body 22 (which is of main importance, lids being much shallower), irrespective of the dimensions, taking into consideration various commercial sizes of cases now in use ranging from the smallest size of approximately 12 inches in length by 10 inches in breadth, and 4 inches in depth, to approximately 28 by 16 by 9 inches.

Tools 23 associated with the table 1 are alike in constructions, and are fixed upon slides 24 fitting within longitudinal dove-tailed grooves 24' within said table 1 whose upper surface is provided with notches 25 to be engaged by lever catches 26 carried by said slides to accurately position the slides with respect to the top tools 55

15, said slides being provided also with clamping screws 27 cooperating with clamping plates 27' arranged in the dove-tailed grooves 24' to secure the adjusted position. Said tools are each provided with a recess 28 to accommodate the pronged-fastening lock 29 and a material-penetrating punch 30, said slides and tools being constructed and applied to the table substantially in accordance with my patent referred to.

10 As usual, a transversely adjustable back stop 31 and a longitudinally adjustable side stop 32 are associated with the table 1, the former to provide an abutment for one longitudinal edge 33, and the latter forming an abutment for one end 15 34 of said case body 22, whereby the front or wall 35 of said case body is accurately positioned in relation to the tools to ensure that the fastenings are secured to said case body at predetermined localities. The back stop 31 is transversely 20 slidable along dove-tailed grooves 31¹ in the table 1 and is fixable in any convenient position by clamping screws 31² and co-operative clamping plates 31³ in said grooves 31¹. The side stop 32 is longitudinally slid able along a dove-tailed 25 groove 32¹ in the front of the table 1 and is fixable in any convenient position by clamping screws 32² and co-operative clamping plates 32³ mounted in said groove 32¹.

The plunger head 5 may be lifted and lowered by any convenient means. By way of example, the drawing illustrates a lever 36 fulcrumed at 37 to the rigid pillar 3 of the press frame and connected at one end to a link 38 of a treadle mechanism (not shown) and connected at its other end directly with a slot 39 in the carrier 6 which is fast with the plunger head 5.

It will be readily apparent to those skilled in the art that by constructing the upper tools 15 compactly and offsetting them forwardly upon the carrier 6, said tools can operate inside the body of a case without fear of the tools fouling or damaging the material of the case.

It will be appreciated that as the top tools are
slidable from end to end on the carrier and to
any intermediate position thereon, a single pair
of top and bottom tools may be adjusted and
fixed in a central position on the machine for
use in fixing single fastenings to case bodies and
lids, the size of which calls for single co-opera-
tive fastenings only.

The operation of simultaneously fixing a pair of fastenings to a case body is as follows:

The slides 24 and the tool holders 7 are adjusted to bring each pair of top and bottom tools into vertical alignment and into predetermined spaced positions to suit the particular size of case to which the fastenings are to be fixed, such positions being maintained by the aforesaid devices. The fastenings 29 are then placed prongs-
upward in the recessed bottom tools when the aforesaid material penetrating punches 30 engage the hole 41 in the front and back plates of each fastening and localizes the latter in said

recess. The case 22 is held in position up to the stops 31, 32 and the mechanism actuating the plunger head is set in operation. As the plunger head descends and with it the top tools 15, each pressure plate 17 causes the prongs 42 of the fastenings 29 to pierce the material of the case body, the springs 18 offering sufficient resistance to allow the prongs of the fastenings to pierce the material and lift the pivoted flaps 19 and finally, with continued downward movement of the plunger head, the clinching pegs 20 clinch the prongs 42 against the inner wall of the case by means of the aforesaid pivoted flaps.

Having now described my invention, what I claim and desire to secure by Letters Patent is: 15

1. Machine for fixing pronged fastenings to bodies and lids of attaché cases and the like, comprising in combination a table, bottom tools associated with and mounted for longitudinal adjustment on said table and adapted to receive fastenings in the prong-upward position, a plunger, means for actuating said plunger, a horizontal carrier movable with said plunger, tool holders mounted for adjustment on and along said carrier, forwardly offset projections on said tool holders, and tools applied to said projections to operate within a case body or lid. 20 25

2. A machine for fixing pronged fastenings to bodies and lids of attaché cases and the like, comprising in combination a table, bottom tools associated with and mounted for longitudinal adjustment on said table and adapted to receive fastenings in prong-upward position, a plunger, means for actuating said plunger, a horizontal carrier movable with and disposed forwardly of said plunger, tool holders slidably mounted on said carrier for adjustment from end to end thereof, forwardly offset projections on said tool holders, and tools applied to said projections to operate within a case body or lid. 40

3. A machine for fixing pronged fastenings to bodies and lids of attaché cases and the like, comprising in combination a table, bottom tools associated with and mounted for longitudinal adjustment on said table and adapted to receive fastenings in prong-upward position, a plunger, means for actuating said plunger, a horizontal carrier movable with and disposed forwardly of said plunger, tool holders slidably mounted on said carrier for adjustment from end to end thereof, forwardly offset projections on said tool holders, said projections having vertical gaps in their forward ends, and sleeve-like tools fitted to the ends of said tool holders, each tool comprising a pressure spring received in said gaps of said projections, said tools being adapted to operate within a case body or lid. 45 50 55

4. A machine according to claim 1, comprising further a back stop and a side stop respectively providing abutments for one longitudinal edge 60 and one side wall of a case body or lid.

CHARLES WILLIAM CHENEY
